UNITED STATES PATENT OFFICE.

THOMAS EDWIN UNKS, OF SANDUSKY, OHIO.

GEARING.

1,110,840.

Specification of Letters Patent. Patented Sept. 15, 1914.

Application filed July 15, 1912. Serial No. 709,571.

To all whom it may concern:

Be it known that I, THOMAS E. UNKS, a citizen of the United States of America, residing at Sandusky, in the county of Erie 5 and State of Ohio, have invented certain new and useful Improvements in Gearing, of which the following is a specification.

This invention relates to certain new and useful improvements in washing machines, 10 and the primary object of the invention is to provide an improved machine of this type in which the rub-board is perforated and is maintained stationary, while the tub is given alternating rotary and vertical movement, 15 to effect squeezing of the clothes and passage of the water through the rub-board when the tub is moved upwardly, and upon downward movement of the tub to form a partial vacuum between the tub and rub-board 20 whereby the water is drawn through the rub-board with great force, thereby causing same to pass through the clothes.

In the drawings: Figure 1 is a top plan view of the invention; Fig. 2 is a side elevation; Fig. 3 is a top plan view with the tub removed; Fig. 4 is a longitudinal sectional view of Fig. 3; Fig. 5 is an enlarged fragmentary detail view, partly in section of one end of the rub-board supporting bar and the holding means thereof; and Fig. 6 is a similar view of the opposite end of said bar and the holding means thereof. Fig. 7 is an elevation of one of the cam-shaped gears.

The frame of the machine is preferably 35 formed of angle-bars and comprising the vertical legs 1, and horizontal connecting members 2. A horizontal plate 3 is connected to the frame and has a central bearing 4 and end bearings 5 and 6 secured to its upper face. An idler segmental gear 7 is loosely mounted on a stub shaft 8 that is journaled in bearing 5 and one end of central bearing 4, and a similar segmental operating gear 9 is keyed to an operating shaft 45 10 that is journaled in the other end of the central bearing 4 and the end bearing 6. A master gear wheel 11 meshes with the segmental gears 7 and 9 and has pins 12 on its upper face for engagement in apertures, 50 provided for the reception thereof, in the bottom of the tub 13. The master gear wheel 11 has a shaft 14 secured thereto and depending therefrom, the shaft being slid- 55 ingly received in openings provided there- for in the plate 3, and in the base of the central bearing 4. A coil spring 15 encircles

the lower end of shaft 14 and at its upper end abuts the under face of the plate 3, while its lower end carries a bearing 16 upon which the shaft 14 rests. 60 The function of the spring being to exert upward pressure on the tub to assist the operator in raising the tub and contents and preventing a jerking movement when the tub is on the downward movement also 65 equalizing the amount of energy required in the upward and downward movement.

When movement is imparted to the segmental gears through the mechanism herein-after described, a combined oscillating and vertical movement is imparted to the tub. This is accomplished by gears 7 and 9 which are formed cam shape. As said gears are in mesh and in contact with the master gear wheel which is in turn attached to the tub, a 70 rotary movement is transmitted to the tub by the gear teeth and at the same time the tub is forced upward by one of the cam shape gears as shown in Fig. 4 dotted line. The tub is forced to descend by its own 75 gravity and the tension of the spring 15 when the cam shape gears 7 and 9 move downwardly.

Shaft 10 has a socketed member 17 attached thereto to receive the hand operated lever 18, by means of which latter the shaft 10 is given oscillatory movement. A short arm 19 is formed integral with member 17 and has one end of a connecting rod 20 pivoted thereto, the opposite end of which rod 90 20 is pivoted to a crank-pin 21 of a gear wheel 22 mounted in a bearing 23 that is connected to the frame. The gear wheel 22 meshes with a pinion 24 that is connected to a fly wheel 25, the fly wheel and pinion 95 thereof being mounted on a shaft that is journaled in a bearing 26 secured to the frame.

The rub-board 27 is perforated as depicted in Fig. 1 of the drawings and is ad- 100 justably suspended from a vertical rod 28 that is secured to a cross bar 29 by means of a clamp 30. One end of the cross bar 29 is formed of T-shape in cross section as shown in Fig. 5 of the drawings, and has 105 the leg of the T received in an opening 31 that is formed in a plate 32 secured to the upper end of one of the legs 1 of the frame. The plate 32 is formed with a hook-shaped mem- 110 ber 33 that overlies the cross bar 29 in spaced relation thereto. The opposite end of the cross bar 29 is forked as shown at 34

in Fig. 6 and receives the leg of a T-shaped member 35 that is formed on a plate 36 secured to the leg 1 of the frame that is diagonally opposite to the leg which has plate 32 attached thereto.

What is claimed is:

1. In a device of the type set forth, a frame, an idler cam shaped segmental gear mounted thereon, an operating shaft having a cam shaped segmental gear also mounted on the frame and rigidly connected to said shaft, a master gear in mesh with both of said segmental gears, a spring held shaft depending therefrom, a member connected to the operating shaft, a hand lever connected to said member, said member having a depending arm, a gear wheel, a connecting rod connected at its ends to said arm and said last named wheel, and a fly wheel having a pinion in mesh with said last named gear wheel; said mechanism being adapted to impart a combined oscillating and vertical movement to the spring held shaft.
- 20

2. In a device of the type set forth, a frame, an idler segmental gear journaled on the frame, an operating shaft having a segmental gear rigidly connected therewith, a master gear in mesh with both of said segmental gears and having a spring held shaft depending therefrom, a member connected to the operating shaft, a fly-wheel, and means to operate said fly-wheel from said member; said mechanism being adapted to impart a combined vertical and oscillating movement to the spring held shaft. 35

3. In a device of the type set forth, a vertically movable spring held master gear, and means in mesh with said gear for supporting the same and for imparting alternating rotary and vertical movement thereto. 40

In testimony whereof I affix my signature in presence of two witnesses.

THOMAS EDWIN UNKS.
